SOCK OR HALF HOSE

Filed Oct. 6, 1924

Inventor,
Harry L. Kinne
By *W. H. Stauden* her Atty.

UNITED STATES PATENT OFFICE.

HARRY LOVELAND KINNE, OF OAK PARK, ILLINOIS.

SOCK OR HALF HOSE.

Application filed October 6, 1924. Serial No. 741,959.

To all whom it may concern:

Be it known that I, HARRY LOVELAND KINNE, a citizen of the United States, residing at Oak Park, in the county of Cook and State of Illinois, have invented certain new and useful Improvements in Socks or Half Hose, of which the following is a specification.

This invention relates to socks or half-hose such as worn by infants and children.

The ordinary sock of knitted cotton, lisle, silk, fiber, wool, or combination of any or all of such materials will not remain up, despite the springiness or inherent resiliency of knitted material.

Consequently, while the ordinary sock or half-hose is commonly provided with a top knitted for the purpose of elastically engaging the child's leg for the purpose of holding the sock up, nevertheless the sock slips down around the child's or infant's shoe top and presents an unsightly appearance. Garters have been resorted to for the purpose of overcoming this tendency but unless they are uncomfortably tight, they do not properly hold the sock up on the leg.

The object of my invention is to provide a sock or half-hose for infants and children which will have means whereby the leg part thereof will remain up when the sock is worn, present a neat and dressy appearance, have no tendency to settle or slip down over the shoe tops and will obviate the necessity for using garters.

The invention is carried out by providing the sock with a leg in the form of a cuff comprising a plurality of thicknesses, folds, or rolls, the cuff being so constructed that it will firmly, yet comfortably, grasp the leg of the child and will possess a certain stiffness preventing it from falling or settling around the shoe top, while being of such height or length that it will serve as a leg part and yet will not require a garter.

In carrying out the invention, I do not limit the cuff to any number of thicknesses, rolls, folds, or plies but intend the claim, unless otherwise specified, to cover such a number of rolls, thicknesses, folds, plies, or the like as may be found necessary, according to the size of sock and material of which it is made. Nor is the sock limited to any material as it may be knit from cotton, lisle,

silk, fiber, wool, or a combination of any or all of said materials.

In practice, the folds of the cuff may occur where there is provided transversely arranged knitted ribs, said ribs being circular and extending crosswise in relation to the vertical ribs of the cuff.

The provision of the circularly arranged ribs not only defines even folds for the cuff but insures that degree of stiffness in the cuff that prevents the cuff from falling down or sagging and yet the circular ribs being elastic, they do not interfere with the elastic gripping action of the cuff.

One embodiment of the invention is set forth hereinafter and disclosed in the accompanying drawings, in which:

Figure 1, is a side elevation of the sock when ready for use;

Fig. 2, is a similar view, showing the leg opened out to better illustrate the circular ribs; and

Fig. 3, is a vertical section through the cuff of the sock, showing the folded thicknesses or plies.

The sock or half-hose has the usual foot 1, knitted in any usual or preferred manner.

The leg 2 is of knitted material, being tubular and, when extended as shown in Fig. 2, it is of about the usual length. The leg may be provided with knitted, circularly arranged ribs 3 which, in the embodiment shown in the drawings, subdivide the leg into three sections. It will be understood, however, that the invention is not limited to the use of the ribs 3, nor to any number of folds, rolls or thicknesses constituting the cuff.

The leg 2 is preferably provided with vertical or lengthwise extending ribs 4 to afford the requisite springiness or clinging tendency.

The cuff, as shown in Figs. 1, 3, is of sufficient length to constitute a stocking leg for infants' and children's half-hose and yet it does not sag or fall down and at all times presents a neat and dressy appearance, while being comfortable and obviating the necessity of using garters.

I am aware that full length stockings have been provided with cuff tops intended for use in connection with garters; further, that it has been a common practice to fold or

roll the tops of stockings over garters but my invention dispenses entirely with the use of garters and is particularly intended for embodiment in socks for infants' and children's wear.

The sock may be knitted from any material, or combination of materials, as previously set forth.

I claim:

- 10 A sock comprising solely a foot, and an elastic self-retaining cuff located immediate-

ly above said foot, the cuff being knitted and provided with longitudinally extending stiffening ribs throughout its length, and also provided with spaced, circularly arranged knitted ribs at different heights defining folding regions for the plurality of overlying sections which compose the cuff.

In testimony whereof I affix my signature.

HARRY LOVELAND KINNE.
